UNITED STATES PATENT OFFICE.

HOWARD D. COLMAN, OF ROCKFORD, ILLINOIS, ASSIGNEE TO BARBER-COLMAN COMPANY, OF ROCKFORD, ILLINOIS, A CORPORATION OF ILLINOIS.

THREAD-HANDLING MECHANISM.

Application filed September 26, 1924. Serial No. 740,013.

This invention relates to machines for operating upon warps, as, for example, machines for drawing warp threads through the eyes of loom harnesses. A machine of the above 5 mentioned type is disclosed in the Field, Hathaway and Lanning Patent No. 871,680, dated November 19, 1907. It is customary in such machines to employ a needle having a hook to receive the thread to be drawn 10 through the harness eye, and to provide means for turning the needle to enable the hook to receive the thread.

A particular object of the present invention is to adapt a warp-drawing machine for operation upon wire heddles. Such heddles have eyes which are too narrow to receive the cylindrical needle heretofore commonly used in warp-drawing machines. I therefore provide a thin flat needle of such cross- 20 sectional dimensions as to enable it to enter the eyes of wire heddles. Inasmuch as the needle cannot be turned while in the heddle eye to grasp the thread which is to be drawn through the eye, I provide means for so positioning the thread that it shall be caught in the hook of the needle without any necessity for turning the latter.

The usual speed of operation of the needle is 250 reciprocations per minute. The means 30 heretofore provided to give the needle a partial rotation near the outer end of its forward stroke has consisted of a guideway having a quarter-turn near its forward end and a pin projecting from the needle holder and 35 traveling in said guideway. Near the forward end of the needle stroke said pin entered the curved portion of the guideway and thus caused the needle holder and the needle to turn through an arc of ninety degrees. On 40 the return stroke the pin again engaged the curved portion of the guideway and restored the needle holder and the needle to normal position. As will be readily understood, the striking of the pin against the walls of the 45 curved portion of the guideway five hundred times per minute caused objectionable wear and noise. The present invention eliminates these objections, as the need for turning the needle has been obviated.

50 In the accompanying drawings, Figure 1 is an end elevation of a warp-drawing machine embodying the features of my invention.

Fig. 2 is a plan view of the pattern mechanism. 55

Fig. 3 is a fragmental view of the drive for the thread-selecting worms.

Fig. 4 is a fragmental plan view showing the needle projected through a harness eye into engagement with a warp thread. 60

Fig. 5 is a front elevation of the parts shown in Fig. 4.

Fig. 6 is an underside view of the parts shown in Figs. 4 and 5.

Fig. 7 is a vertical sectional view taken approximately in the plane of line 7-7 of Fig. 4.

Figs. 8, 9, 10 and 11 are perspective views illustrating the action of the needle and the devices for enabling the needle to engage the 70 threads.

The machine which has been selected to illustrate the invention is generally similar to the one disclosed in the La Chance and Pennell Patent No. 1,317,204 dated September 23, 1919, although it should be understood that the invention in certain of its aspects is applicable to other machines than warp-drawing machines, as well as to warp-drawing machines of other types than that exemplified by the La Chance and Pennell machine.

The elements to be operated upon by the machine, i. e., the reed, the harnesses, the warp or warps, and the drop wires, if any, 85 are supported in a generally parallel arrangement lengthwise of the machine. The particular machine shown in the drawings is adapted to operate upon four cotton harnesses *h*, a reed (not shown), and two sheets or 90 groups of warp threads. Each harness consists of a plurality of heddles *h'* (Figs. 7 and 11) having eyes *h''*. The heddle eyes are positioned for the passage of the warp-drawing needle by means including worms *h'''* (Fig. 4), there being one worm for each harness.

The warp-drawing needle 3 (Fig. 10) is in the form of a relatively thin flat bar standing on edge. The forward end of the bar 100 is slightly reduced in thickness and has a downwardly-opening thread-receiving hook 3'. The needle is carried by a mechanism carriage 5 which is caused to travel longitudinally of the machine.

The drawing-in needle may be horizontal. 105

ly reciprocated in any suitable manner. As shown herein, it is actuated by means including a crank disk 17 connected by a rod 19 with an arm 21, the lower end of which is fulcrumed on the carriage 5 and the upper end of which is connected by a link 23 with the needle holder which slides in a guide 25. Instead of providing means for giving the needle a partial rotation near the outer end of its stroke, as heretofore, the needle is reciprocated with its hook 3' continually directed downwardly.

The warp threads are positioned for reception in the hook 3' by means including two warp worms 57 and 59 mounted on shafts 61 and 63, respectively. Each warp worm comprises a frusto-conical fluted portion which first receives, disentangles and separates the warp threads and a selecting, spacing and feeding screw or worm portion by which the threads are presented to the hook of the drawing-in needle successively. For a more detailed description of the warp worms, reference may be made to the Field Patent No. 1,282,059, dated October 22, 1918, and the Field and Lanning Patent No. 1,305,705, dated June 3, 1919.

The harness worm rods h^4 and the warp worm shafts 61 and 63 are journaled in bearings on the mechanism carriage 5, the bearings for the warp worm shafts being formed in a bracket 5' on the carriage 5.

The reed opener (not shown), the harness worms h^3 and the warp worms 57 and 59 are driven by means under the control of a suitable pattern mechanism (Fig. 2), which mechanism is generally similar to that fully described in the Lea Patent No. 1,417,078, dated May 23, 1922.

The two sheets of warp threads 109 and 119 are led from warp beams 111 and 121 through a clamp 113 mounted on a carriage 115. From the clamp 113 the sheet of warp threads 109 extends around the worm shaft 61 to a clamp 117 adjustably mounted on rods 118 projecting from the carriage 115. The sheet of warp threads 119 extends from the clamp 113 around the worm shaft 63 to the clamp 117, in which latter clamp they are held loosely. The warp threads may be put under proper tension for the operation of the feeding, separating and selecting worms by adjusting the clamp 117 along the rods 118. While the same clamps are herein utilized for both groups of threads, it will be understood that separate clamps may be used for each group, if desired, as indicated in the Hathaway and Mars Patent No. 1,379,099, dated May 24, 1921.

As shown in Figs. 7 and 10, each warp worm presents to the inspection of the operator a series of spaced or separated threads prior to their successive engagement by the drawing-in needle, the threads extending in a generally vertical plane between the warp

worm and the clamp 113. As shown in Fig. 5, the needle is reciprocated between the foremost two threads of the series. In order to position the foremost thread so that it shall spring into the hook 3' as the needle is retracted, I provide, in conjunction with each of the warp worms, a device operating below the horizontal plane of reciprocation of the needle to deflect the foremost thread laterally of the needle (as shown in Fig. 9) so as to bend the thread under the needle, whereby, upon the retraction of the needle, the thread will spring up into the hook 3' (as shown in Fig. 10). These thread-deflecting devices are supported upon a bracket 122 which is pivoted to the bracket 5' at 123 (Figs. 5 and 6). The bracket 122 carries a stop 124 (Fig. 5) arranged to coact with a stop screw 125 on the bracket 5' for the purpose of accurately locating the thread-deflecting devices with relation to the needle and the thread. The bracket 122 is held in operative position by means of a contractile spring 126 connected at 127 to the bracket 122 and at 128 to the bracket 5', the point 127 being above a line passing through the points 123 and 128 when the bracket is in normal position. For convenience in loading the machine the bracket 122 may be swung down until the point 127 is below said line, a stop 129 on the bracket being then in contact with the bracket 5'.

The thread-deflecting device associated with the warp worm 57 comprises an arm 130 (Fig. 6) pivoted to the bracket 122 at 131 to swing in a horizontal plane and carrying a pin 132 (Fig. 7) that engages a cam 133 which is rigid with the warp worm. Rigid with the arm 130 is a sheet metal finger 134 arranged to engage the foremost thread and deflect it under the needle.

Associated with the warp worm 59 is a thread-deflecting arm 135 pivoted to the bracket 122 at 136 to swing in a horizontal plane and provided with a pin 137 that engages a cam 138 connected to said warp worm. The arm 135 has a sheet metal finger 139 adapted to engage the foremost thread selected by said worm and bend it under the needle.

As shown in Fig. 7, the deflectors 134 and 139 each present a plain edge to the foremost thread, said edge extending across the plane of the warp (see Fig. 4), so that the foremost thread bears against said edge upon relative approaching movement of the thread and the deflector. Each worm and its cooperating deflector hold that portion of the foremost thread which extends between the worm and the deflector in an inclined position so that it is bent under the needle and toward the companion spaced threads.

When the bracket 122 is in its down position, the arms 130 and 135 are prevented from swinging too far out of proper position to en-

gage the cams 133 and 138 when the bracket is returned to normal position, by means of stop screws 140 carried by the bracket 122, said screws having flanges that project into 5 slots in the ends of said arms.

In operation, the warp worms are rotated in proper sequence to place threads from the beams in position to be taken by the needle 3 in the desired order. The needle enters 10 between the foremost pair of threads of a given warp and relatively close to the foremost thread of the pair. As the warp worm comes to rest after advancing said threads, the cam 133 or 138, as the case may be, swings 15 the thread-deflecting finger below the needle, thereby bending the foremost thread member of the needle. When in the retraction of the needle, the hook 3' reaches the deflected thread, the latter springs up into the hook 20 and is drawn out of the clamp 117 and through the heddle eye and the reed space.

I claim as my invention:

1. A thread-handling mechanism having, in combination, a rotary thread-selecting 25 worm, a hooked drawing needle movable into position alongside a thread selected by said worm, a cam connected to rotate with said worm, a pivoted bracket, a deflector mounted on said bracket and arranged to be moved 30 by said cam to bend said thread across the needle whereby upon retraction of the needle the deflected thread springs into the hook, and a spring for yieldingly holding said bracket in operative position.

35 2. A thread-handling mechanism having, in combination, a rotary worm for selecting threads from a warp and presenting a series of spaced threads, a hooked drawing needle reciprocable between the foremost pair of 40 spaced threads, a cam connected to rotate with said worm, and a deflector arranged to be swung by said cam to bend the foremost thread across the needle whereby, upon retraction of the needle, the deflected thread 45 springs into the hook.

3. A thread-handling mechanism having, in combination, a rotary worm for selecting threads from a warp and presenting a series of spaced threads, a drawing needle in the 50 form of a relatively thin flat bar having a hook in its lower edge and rectilinearly reciprocable between the foremost pair of spaced threads, and a deflector to bend the foremost thread under the needle whereby upon retraction of the needle the deflected thread 55 springs up into the hook, said deflector having a disengageable driving connection with the worm.

60 4. A thread-handling mechanism having, in combination, a selector for selecting threads from a warp, a drawing needle in

the form of a relatively thin flat bar having a hook in its lower edge and rectilinearly reciprocable into position adjacent to the foremost selected thread, and a deflector to 65 bend said thread under the needle whereby upon retraction of the needle the deflected thread springs up into the hook said deflector having a disengageable driving connection with the selector.

5. A thread-handling mechanism having, in combination, a rotary thread selecting worm, a hooked drawing needle movable into position alongside a thread selected by said worm, a cam connected to rotate with said worm, a movable support, a deflector mounted on said support, a pin on the deflector to engage said cam and withdrawable from the cam on movement of said support, said deflector being arranged to bend a selected thread 70 across the needle whereby upon retraction of the needle the deflected thread springs into the hook, and means to limit movement of the deflector when the pin is out of engagement with the cam.

6. A thread-handling mechanism having, in combination, a thread selector, a hooked drawing needle movable into position alongside a thread selected by said worm, a cam, a movable support, a deflector mounted on 75 said support, and a pin on the deflector to engage said cam and withdrawable from the cam on movement of said support, said deflector being arranged to bend a selected thread 80 across the needle whereby upon retraction of the needle the deflected thread springs into the hook.

7. A thread-handling mechanism having, in combination, a rotary worm for selecting threads from a warp and for presenting a 85 series of spaced threads, a drawing needle in the form of a relatively thin flat bar having a hook in its lower edge and rectilinearly reciprocable between the foremost pair of spaced threads, and a deflector located below 90 the path of the needle and presenting a plain edge to the foremost thread, said edge extending across the plane of the warp so that the foremost thread bears against said edge upon relative approaching movement of said 95 thread and the deflector, said worm and deflector cooperating to hold that portion of said foremost thread which extends between the worm and the deflector in an inclined position so that it is bent under the needle and toward the companion spaced threads, whereby upon retraction of the needle the deflected threads springs up into the hook.

In testimony whereof, I have hereunto affixed my signature.

HOWARD D. COLMAN.
